UNITED STATES PATENT OFFICE.

GEORGE B. McINROY, OF OAKLAND, CALIFORNIA.

DESIGN FOR A CONFECTIONERY-VENDING STAND.

Application filed July 6, 1925. Serial No. 14,002. Term of patent 7 years.

To all whom it may concern:

Be it known that I, GEORGE B. McINROY, a citizen of the United States, residing at Oakland, in the county of Alameda and State of California, have invented a certain new, original, and ornamental Design for Confectionery-Vending Stand, of which the following is a specification.

Referring to the accompanying drawing which forms a part hereof,

I claim:

The ornamental design for a confectionery vending stand, substantially as shown.

In testimony whereof I affix my signature.

GEORGE B. McINROY.
